UNITED STATES PATENT OFFICE.

ELBRIDGE J. STEELE, OF NEW HAVEN, CONNECTICUT, ASSIGNOR TO
SARGENT & CO., OF SAME PLACE.

DESIGN FOR LOCK-FRONT.

Specification forming part of Design No. 6,723, dated June 24, 1873; application filed May 13, 1873.

To all whom it may concern:

Be it known that I, ELBRIDGE J. STEELE, of New Haven, in the county of New Haven and State of Connecticut, have invented a new Design for Lock-Front; and I do hereby declare the following, when taken in connection with the accompanying drawings and the letters of reference marked thereon, to be a full, clear, and exact description of the same, and which said drawings constitute a part of this specification, and represent in—

Figure 1, a front view; and in Fig. 2, a central section.

This invention relates to a design for the ornamentation of the fronts of mortised locks and latches; and it consists in a raised tracery upon a flat matted surface, the said tracery being distant from the edge of the plate, so as to leave a margin entirely around the plate on a level with the other portions of the main surface, substantially as shown in the accompanying drawings, and as fully hereinafter described.

The front is constructed with openings for the bolts, according to the nature of the lock,

and with a screw-hole, *a*, at each end. The plate is ornamented by tracery projecting from the surface, and so as to leave a space between the tracery and the edge around the plate level with the other portion of the surface; the whole surface of the plate, except the tracery, matted, to give relief to the tracery. The tracery is polished and may be plated or otherwise finished.

It will be understood that the matted surface is flat or level throughout, including the space outside the tracery to the edge of the plate, and that the ornamentation projects therefrom, as seen in Fig. 2.

The particular style of tracery is no part of this design, as that may be varied according to the taste of the manufacturer or demands of the trade.

I claim as my invention—

The design for lock-front, as herein described, and shown in the accompanying illustration.

ELBRIDGE J. STEELE.
